UNITED STATES PATENT OFFICE.

LEONARD MAURICE EDWARD DENT AND ALECK MACKENZIE, OF LONDON, AND JOHN WHITE, OF SUNNINGDALE, ENGLAND.

GOLF TEE.

Application filed September 9, 1924, Serial No. 736,697, and in Great Britain August 21, 1924.

This invention is for improvements in or relating to golf tees of the type comprising a cup-shaped head to receive the ball and a stem to be pressed into the ground. The 5 invention has for one of its objects to provide a construction of tee of this type which shall not be liable to be displaced very far from its position when the ball is hit. In this way the likelihood of the tee being lost 10 is minimized.

According to one feature of the invention there is provided a tee of the type above described which is characterized by the provision upon the stem of one or more 15 barbs, flukes or hooks, hereinafter referred to as barbs. When the stem is pressed into the ground in setting up the tee, the barb or barbs will be buried and when the ball is hit and the tee displaced, the barbs will 20 tend to resist such displacement by taking an anchorage in the ground.

Another object of the invention is to provide means for indicating to the player whether the caddy has set up the tee in the 25 most advantageous manner, and a further object of the invention is to provide against the tees damaging the club face.

For a more complete understanding of the invention there will now be described, 30 by way of example only and with reference to the accompanying drawings, certain constructional forms of tee according to the invention. It is to be understood, however, that the invention is not restricted to the 35 precise constructional details illustrated.

In these drawings—

Figure 1 is a perspective side elevation of one form of tee, the drawing being on an enlarged scale;

40 Figure 2 is an end elevation of the construction shown in Figure 1;

Figure 3 is a perspective view corresponding to Figure 1 of a modified form of tee;

45 Figure 4 is a similar view of a further modification; and

Figure 5 a similar view of still another modification.

Like reference numerals indicate like 50 parts throughout the drawings.

In the construction shown in Figure 1, the tee comprises a cup-shaped head 10 to receive the ball and a stem 11 which is intended to be pressed into the ground. The 55 lower end of the stem is sharpened at 12,

and by reference to Figure 2, it will be seen that the stem throughout a considerable portion of its length is relatively thin so as to be capable of being easily pressed into the ground. Starting from the lower end 60 of the stem is a barb, fluke or hook 13 which has a blunt end 14 and lies more or less parallel to the stem 11.

When the stem is pressed into the ground in setting up the tee, the barb 13 will be 65 buried, and when the ball is hit and the tee displaced, the barb will tend to resist such displacement by taking an anchorage in the ground. Thus it is unlikely that the tee will be entirely withdrawn from the ground 70 by the club, but if it should be, the distance it will be moved will in all probability be quite small, owing to the dragging effect exerted by the barb.

Only a single barb is employed in the 75 construction shown in Figure 1, but the stem may have more than one barb if so desired. For instance, in Figure 3, the stem 11 is shown as having two barbs 13 and 15 on its opposite sides. In this figure, moreover, the two barbs are shown as starting from different points along the length of the stem 11, although, of course, this arrangement is not essential.

Where only a single barb is provided on 85 the stem 11, to obtain the maximum effect from it, the tee should be set up in such a position that this single barb lies at the front of the tee, i. e. faces towards the direction of travel of the ball. To enable the 90 player to see that the caddy has set up the tee in this most advantageous manner, the head 10 on that side of the stem on which the barb is situated may be made of a shape different from its shape on the opposite side 95 of the stem. Such a construction is shown in Figure 4, in which the head 10 is formed with a pointed portion 16 on its side above the barb 13.

As already explained, the stem 11 will 100 usually be made quite small in diameter. Furthermore, the head 10 will usually be quite thin in depth. To avoid damage to the face of the club by a sharp edge on the head 10, this latter may be made of bulbous 105 or similar flattened or well-rounded formation, such as 17 (Figure 5) at the part likely to be hit. Where the barb or barbs are only on one side of the stem 11, the head at the other side of the stem may be of this 110

bulbous formation so as to serve the double purpose of avoiding damage to the club and indicating the most effective setting for the tee.

5. It is preferred to make the tees of metal such as aluminium, which, while not being liable to be broken or rusted, is also sufficiently bright in appearance to be readily seen and picked up after use.

10. It is to be understood that the invention is not restricted to the precise constructional details set forth.

What we claim as our invention and desire to secure by Letters Patent is:—

15. 1. An aluminium golf tee comprising a cup-shaped head to receive the ball, a stem sharpened to a point to be pressed into the ground and a barb upon said stem, for the purpose specified.

20. 2. An aluminium golf tee comprising a cup-shaped head to receive the ball, a stem flattened towards its point to be pressed into the ground and barbs upon said stem, for the purpose specified.

25. 3. A golf tee comprising a cupped head to receive the ball, a stem to be pressed into the ground and barbed on one side, and means on said head for indicating the side of the stem which is barbed.

30. 4. A golf tee comprising a stem to be

pressed into the ground and having a barb on one side, and a head to said stem which is cupped to receive the ball and on the side of the stem at which the barb lies is of a shape different from its shape on the opposite side of the stem, for the purpose specified. 35

5. A golf tee comprising a barbed stem to be pressed into the ground and a cupped head to receive the ball, said head being of 40 bulbous shape at one side, for the purpose specified.

6. A metal golf tee comprising a cup-shaped head to receive the ball, which head is of bulbous shape on one side, and a stem 45 to be pressed into the ground, which stem is barbed on the side opposite to the bulbous part of the head, for the purpose specified.

7. A golf tee comprising a head shaped to receive a ball, and a single stem constituting an anchor therefor, which stem is flattened and pointed at its end and carries a fluke which lies in the general plane of the flattened portion of the stem. 50

In testimony whereof we affix our signatures. 55
